WEARING APPAREL

John Muhr, Osborn, Ohio

Application January 4, 1939, Serial No. 249,232

1 Claim. (Cl. 2-70)

This invention relates to wearing apparel and more particularly to an upper garment and a lower garment, such as a shirt and a pair of trousers.

An object of this invention is to provide an upper garment and a lower garment united along the belt with a slide fastener.

Another object of this invention is to provide a juncture between the shirt and the trousers, which juncture is formed by a concealed slide fastener.

Another object of this invention is to provide an upper garment member and a lower garment member joined at the waist line by a slide fastener concealed by a belt integral with one of the garments.

Another object of this invention is to provide a combined shirt and trousers assembly that is economically produced, neat in appearance, simulating conventional shirts and trousers; but at the same time, more dependable and comfortable to wear.

Other objects and advantages reside in the construction of parts, the combination thereof and the mode of operation, as will become more apparent from the following description.

In the drawing,

Figure 1 discloses a fragmentary, perspective view of the preferred embodiment, with the belt loosened.

Figure 2 discloses a fragmentary, perspective view of a modification, with the belt in position.

Figure 3 is a cross sectional view of the juncture at the waist line of a shirt with a pair of trousers, taken substantially on the line 3-3 of Figure 1, wherein the belt concealing the slide fastener is integral with the trousers.

Figure 4 is a cross sectional view similar to Figure 3, showing a modification, wherein the belt is integral with the shirt.

Figure 5 is a cross sectional view of another modification, showing the belt secured in position along the upper edge of the trousers.

Figure 6 discloses a cross sectional view of the upper portion of the trousers, showing a method of attaching the belt for concealing the slide fastener.

In the past it has been conventional style for men to wear a shirt that reaches a considerable distance below the waist line, which shirt is tucked beneath the trousers. While working, or for that matter while at play, there is a tendency for the shirt to work out of the trousers, especially when the clothing is made from certain types of materials which have a tendency

to creep. For some types of working clothes this difficulty has been overcome by the use of what is generally referred to as unionalls or overalls, where the trousers and upper garment suspended from the shoulders are made into a unitary piece. Generally such garments are made of a common material, that is, the materials of the upper portion and the lower portion of the garment are the same. Such garments are ideally suited for some types of workmen, such as mechanics and the like. On the other hand, such garments are not suited and are not well received by the public where a neater attire is required.

This has been overcome in the preferred embodiment and the various modifications shown herein, by providing a waist length shirt having a stringer provided with metallic interlocking members cooperating with like metallic members attached to another stringer sewed to the top of the trousers to hold the shirt and trousers together along the waist line. For some purposes, these stringers, cooperating to form a slide fastener, may be concealed by a belt that may be made from the same material as the trousers, or the same material as the shirt, or a different material, which belt conceals the fastener, so that the finished article simulates a conventional shirt used with conventional trousers. This results in a very dependable structure, saves materials, in that the length of the shirt may be shortened, eliminates the use of suspenders and if desirable, eliminates the use of an extra belt. The resulting structure eliminates the creeping effect of shirttails and insures a positive union between the shirt and the trousers.

Referring to Figure 1 disclosing the preferred embodiment, the reference character 1 indicates a waist length shirt attached to the trousers 2 along the waist line by a slide fastener. This slide fastener has been shown schematically in Figure 1. Referring to Figure 3, the juncture between the shirt 1 and the trousers 2 may include a fastener consisting of metallic interlocking members 3a and 4a disposed along the edges of stringers 3 and 4 respectively extending along opposite sides of the slit between the shirt 1 and the trousers 2. These metallic members are made to join by means of a slide 20 shown schematically in Figure 1. This slide engages the projections and the recesses of the interlocking members 3a and 4a and fasten the two stringers and their respective garments together. The interlocking arrangement is achieved by means of the fitting of projections upon the metallic members into the corresponding recesses. This

type of fastener has come to be known in popular language as "the zipper," probably due to the slider making a hissing sound when it is moved quickly across the stringers.

As may be seen by referring to Figure 3, the stringer 3 is sewed by seam 6 to the lower edge of the shirt 1. The stringer 4 is sewed by seam 6 to a fold along the top of the trousers 2. As may be clearly seen by referring to Figure 3, the trousers have an upwardly projecting reentrant belt-like portion 5, which may be buckled or buttoned in position, so as to conceal the slide fastener. The combined shirt and trousers simulate a conventional shirt and a pair of trousers; but the shirt in the modification disclosed terminates at the waist line, thereby eliminating the use of a tail and saving the material that goes into the manufacture of a tail.

In the modification disclosed in Figure 4, the stringer 3 is sewed to the lower edge of the shirt 1 and the stringer 4 is sewed to the upper part of the trousers 2. A belt 5a in this modification has been attached to the stringer 3 and to the lower edge of the shirt 1, so that when the slide fastener is open and the shirt removed, the belt 5a accompanies the shirt. This permits the use of a contrasting material for the belt portion, or a similar material to the material of the shirt or the trousers, but of a contrasting color.

In the modification disclosed in Figure 5, the belt 7 made from separate material is attached to the upper portion of the trousers, so that the belt is removed with the trousers. This belt is provided with a folded portion extending upwardly from the seam attaching the belt to the trousers and a second folded portion extending downwardly over the top margin of the trousers.

In the modification disclosed in Figure 6, a plurality of belt loops 8, only one of which has been shown, are attached to the upper portion 40 of the trousers and arranged in overlapping re-

lationship with respect to the slide fastener, so that when a belt is passed through the loops this belt will conceal the juncture between the shirt and the trousers.

5 Although the invention has been described principally in connection with a shirt and a pair of trousers, this invention is equally as applicable to other outer garments used by men or women, as for example, it may be used with the waist or blouse and the skirt of a woman's suit or dress, as suggested by the disclosure in Figure 2.

10 Although the preferred modification of the device has been described, it will be understood that within the purview of this invention various changes may be made in the form, details, proportion and arrangement of parts, the combination thereof and mode of operation, which generally stated consist in a device capable of carrying out the objects set forth as disclosed and defined in the appended claim.

15 Having thus described my invention, I claim:

In a garment assembly having an upper garment terminating at the waist line, said upper garment being provided with a stringer and a slide fastener attached along the bottom thereof, said garment assembly including a lower garment, a stringer attached to the top of the main body portion of the lower garment, said second stringer extending upwardly from the top of the main body portion, said stringers being provided with interlocking fastening members secured in position by a sliding member sliding along the stringers, and a camouflaging belt formed by folding the top portion of the material of the lower garment downwardly, then upwardly beyond the top of the main body portion of the lower garment a distance substantially equal to one half the width of said belt so as to conceal the fasteners.

JOHN MUHR.
